US00D622105S

(12) **United States Design Patent**
Koennecke et al.

(10) **Patent No.:** **US D622,105 S**
(45) **Date of Patent:** **** Aug. 24, 2010**

(54) **CUP**

D196,271 S 11/1963 Edwards
D197,313 S 1/1964 Wanderer

(75) Inventors: **Weston Koennecke**, Oak Park, IL (US);
William Hillebrenner, Chicago, IL (US)

(73) Assignee: **Solo Cup Operating Corporating**, Lake
Forest, IL (US)

DESCRIPTION

FIG. 1 is a perspective view showing an embodiment of our new design of a cup;

FIG. 2 is a front view thereof, the rear view being a mirror image thereof;

FIG. 3 is a top view thereof;

FIG. 4 is a side view thereof, the opposite side being a mirror image thereof; and,

FIG. 5 is a bottom view thereof.

The broken lines represent portions of the article that form no part of the claim.

1 Claim, 3 Drawing Sheets
